CLELAND DAVIS, OF THE UNITED STATES NAVY.

TRAJECTORY-REGULATOR FOR PROJECTILES.

1,043,074.

Specification of Letters Patent.

Patented Nov. 5, 1912.

Application filed April 3, 1911. Serial No. 618,764.

To all whom it may concern:

Be it known that I, CLELAND DAVIS, lieutenant-commander U. S. Navy, and a citizen of the United States, and serving on board the U. S. S. *Mississippi*, have invented certain new and useful Improvements in Trajectory-Regulators for Projectiles; and I do hereby declare the following to be a full, clear, and exact description of the invention, such as will enable others skilled in the art to which it appertains to make and use the same.

The present invention relates to projectiles and has for its purpose to provide a means for automatically regulating the flight of projectiles so as to allow for variation in their powder charges, and thus reduce the dispersion of successive shots from the same gun, or from a number of shots of a battery which are fired at the same object.

Among the many difficulties that confront ordnance officers in the development of modern gunnery is the dispersion of the projectiles when fired at long range, due to differences in muzzle velocity, which differences are caused by variations in the ballistic properties of the powder charges; and these ballistic variations are caused in turn by differences in temperature at the time of firing, inherent chemical differences due to methods of manufacture, and differences due to drying out, aging, and the manner of stowing the powder. Efforts to produce uniformity in these respects, or any of them, have not been successful. The importance of regularity in this respect will be appreciated by inspecting, for example, the range tables for a 12 inch, fifty caliber gun, which shows that at 10,000 yards (initial velocity 2700 foot seconds, weight of projectile 870 lbs.) a variation of 50 foot seconds would change the range 280 yards, whereas the danger space at that range for a target 30 feet high is only 80 yards. To overcome or neutralize these disadvantages the present invention proposes to regulate the range by automatically varying the contour of the projectile so as to change the resistance of its passage through the air. The effect or change of the contour of a projectile is well known, and an arrangement by which the contour can be automatically changed will enable a closer approximation to a standard range being attained, corresponding to a specified sight bar height, irrespective of increases in muzzle velocity.

The invention is shown by way of illustration in the accompanying drawings wherein:

Figure 1 is a side elevation of a projectile equipped with the device. Fig. 2 is a central vertical section, partly in elevation, of the device *per se*. Fig. 3 is a transverse sectional view of Fig. 2 taken on the line 3-3. Fig. 4 is a similar view taken on the line 4-4 of Fig. 2. Fig. 5 is a detail view of the resistance plate. Fig. 6 is a top plan view, partly in section, of the contour cap showing the application of the invention. Fig. 7 is a view similar to Fig. 1 showing the resistance devices in operative position, and; Fig. 8 is a front end elevation of Fig. 7.

Referring to the structure in detail and with like characters representing corresponding parts throughout A designates the projectile equipped with a contour cap B, and for the detail construction of which cap reference may be had to my Patent #945,492 and dated January 4, 1910. The cap B is recessed at oppositely disposed points to receive the cylindrical casings 1 which are suitably secured therein, and within which are contained the devices for regulating the trajectory of the projectile.

The regulating devices consist each of a plate or wing 2 mounted to slide radially of the projectile between the guide ways 3 within the casing. The outer edge 4 of the slide plate 2 has the same contour as that of an arc on the immediate adjacent transverse section of the contour cap. A covering 5 closes the casing and has its outer surface lying flush with the exterior surface of the cap B, the purpose whereof will be readily understood.

The means for automatically effecting the release and consequent radial movement of the plate 4 consists of a volute spring 6 secured at one end, by a screw 7, to the base 8 of the casing, and at its free end 9 said spring is connected with a radially movable circuit closing device. This device consists of a support 10 of hard rubber which carries a cross piece or strip 11 of similar material, and said members 10 and 11 are secured to the free end 9 of the spring 6 by a pin 12 (see Fig. 2). A metallic strip 13 is secured against one face of the cross piece 11 and is provided with a plurality of pins 14 (see Fig. 3) which extend through and project beyond the insulated cross piece 11. The projecting ends of said pins are adapted

to have movement within the vertical slots or grooves 15 formed in the face of a rubber plate 16, there being one such groove for each of said pins. The plate 16 is attached by screws 19 to a steel bar 20 that is in turn secured within the casing by screws 21. The several grooves 15 are of gradually increasing length across the face of the plate, and within and adjacent the upper ends of the grooves are located studs 17 designed to contact with the pins 14, and which are in turn connected to firing pins 18 through the medium of conductor wires 19^a, in substantially the manner shown. The contacting of the pins 14 with the studs 17 is designed to close a circuit through the wires 19^a and the firing pins 18, and to this end the non-conductor plate 16 is provided with a metallic strip 15^a against which a pin 16^a carried by the metallic strip 13 has sliding contact. This strip 15^a is connected with the battery C, the other pole of the battery being connected to the ground (see Fig. 2). For each of the firing pins 18 the steel bar 20 is provided with a cartridge 22 adapted to be exploded through the medium of primers 23 on the inner ends of said firing pins as shown in Fig. 3, and for each of the cartridges 22 there is a plunger or pellet 24 loosely mounted within suitable apertures in a steel cross bar 25, which bar is secured within the casing by screws 26, (see Fig. 4). The pellets 24 are held within the apertures by friction plugs 27 (see Fig. 3) that are adapted to be forced out by the pellets on the explosion of the cartridges 22 as will be hereinafter explained. The cross bars 20 and 25 are sufficiently spaced apart to receive the plate or wing 2 and to allow of movement of the same therein. Said plate 2 is provided with a plurality of slots 26 of gradually increasing length and through which pass the pellets 24 that act as stops for limiting the outward radial movement of the plate, but which when successively blown out by the exploded cartridges allow said plate to move outwardly under the influence of centrifugal force.

The operation of the device is as follows:—When the projectile is fired the centrifugal force caused by the rotation of the projectile causes the spring 6 to be deflected and such deflection will be maximum at or near the point of maximum velocity of the projectile, which is shortly after the projectile leaves the gun barrel. Now the amount of deflection of the spring for the desired standard initial velocity is determined and the members 16 and 20 so placed that the centrifugal force generated by the rotation of the projectile at that velocity will cause the circuit closing device to move until the first or innermost contact piece 17 is just clear of the corresponding pin in the cross piece 11, and the amount of this clear-

ance is fixed by the variation in velocity it is desired to regulate. Assume this to be 10 foot seconds, then should the initial velocity be within 10 foot seconds greater than the standard the slidable plate 2 will not move, being held in place by the lowest pellet 24, and the trajectory of the shell will give the normal range. Should, however, the initial velocity reach a point 10 foot seconds greater than the set standard, then contact will be made between the first stud 17 and the corresponding pin 13 working in the groove 15 when the electrical circuit between the battery C and the primer 23 will be completed. The cartridge 23 will then be fired and the pellet 24 forced out of its corresponding aperture in the plate 25. The plate 2 will then be released to move outwardly by centrifugal force until the bottom of the next adjacent slot brings up against its corresponding pellet, thus changing the contour of the surface of the projectile and offering an increased resistance in its passage through the air. The amount of projection is so regulated that the increased resistance retards the flight of the projectile so that at the sight bar height selected it will traverse approximately the same distance as if it had left the gun barrel at the standard initial velocity. In like manner the other contact pieces are brought into circuit closing relation and their corresponding pellets blown out at given increments of initial velocity.

It is obvious that other mechanical means based on the forces generated by the movements of the projectile may be utilized in accomplishing the object sought herein, and I do not, therefore, limit myself to the details shown, but reserve instead the right to make such changes as will better adapt the invention to the purpose in view, except in so far as I am limited by the claims.

What I claim is:—

1. The combination with a projectile, of a device carried thereby and operable to automatically regulate the trajectory of the projectile.
2. The combination with a projectile, of members carried thereby and operable through centrifugal force to automatically regulate the trajectory of the projectile.
3. The combination with a projectile, of plates movably mounted therein and operable through centrifugal force to move outwardly and automatically regulate the trajectory of the projectile.
4. The combination with a projectile having a contour cap, of devices mounted within said cap and operable through centrifugal force to change the contour of said cap and automatically regulate the trajectory of the projectile.
5. The combination with a projectile, of plates mounted therein and operable to move

radially through centrifugal force and regulate the trajectory of the projectile, and electric controlling means adapted to govern the extent of outward movement of said 5 plates, as set forth.

6. The combination with a projectile having a contour cap; of means for automatically regulating the trajectory of the projectile comprising; plates mounted within said 10 cap and radially movable through centrifugal force, stops for variably limiting the extent of movement of said plates, and means for successively removing said stops, for the purpose set forth.

15 7. The combination with a projectile having a contour cap; of means for automatically regulating the trajectory of the projectile comprising; plates mounted within said cap and radially movable through centrifugal force, stops for variably limiting the extent of movement of said plates, and means 20 for successively releasing of said stops, for the purpose set forth.

25 8. The combination with a projectile having a contour cap; of means for automatically regulating the trajectory of the projectile comprising; plates mounted within said cap and movable radially through centrifugal force, stops for variably limiting the extent of such movement, electrically 30 controlled means for successively removing said stops, and centrifugally actuated circuit closing devices associated with said controlling means, for the purpose set forth.

35 9. The combination with a projectile having a contour cap; of means for automatically regulating the trajectory of the projectile comprising; plates mounted within said cap and movable radially through centrifugal force, stops for variably limiting the extent of such movement, cartridges disposed adjacent said stops, and electric means 40 for successively exploding said cartridges to remove the stops, for the purpose set forth.

45 10. The combination with a projectile having a contour cap; of means for automatically regulating the trajectory of the projectile comprising; plates mounted within said cap and movable radially through centrifugal force, stops for variably limiting the extent of such movement, cartridges disposed adjacent said stops, electrically 50 controlled means for successively exploding

said cartridges to remove the stops, and centrifugally actuated circuit closing devices associated with said electric controlling means, for the purpose set forth.

55 11. The combination with a projectile having a contour cap; of means for automatically regulating the trajectory of the projectile comprising; plates mounted within said 60 caps and movable radially through centrifugal force, stops for variably limiting the extent of such movement, cartridges disposed against said stops and adapted to be exploded and remove said stops, primers connected with said cartridges, electric means for igniting the primers in succession, and spring resisted centrifugally actuated 65 devices provided with a plurality of contact points adapted to successively close circuits through, and ignite said primers to explode the cartridges, as set forth.

70 12. The combination with a projectile having a contour cap; of means for automatically regulating the trajectory of the projectile comprising; casings mounted within the cap, a pair of bars secured within each of said casings, a plate provided with graduated slots and mounted between said bars and movable radially through centrifugal force, stops for limiting the movement of said plate consisting of diagonally disposed pellets mounted between said bars and fitting within the slots in the plate, cartridges mounted in one of said bars and disposed against the pellets, an insulated plate secured against said bar, a plurality of contact members mounted on said insulated 80 plate, a contact strip mounted on the insulated plate, a battery connected in circuit with said strip, separate electric connections between said cartridges and the contact members, and a spring resisted centrifugally 85 actuated device having sliding contact with said strip and provided with a plurality of contact points adapted to successively close circuits through said electric connections to explode the cartridges and remove the pellets, for the purpose set forth.

90 In testimony whereof, I affix my signature, in presence of two witnesses.

CLELAND DAVIS.
